Patented Aug. 10, 1920

UNITED STATES PATENT OFFICE.

JOHN W. BINGLEY, OF WATERTOWN, NEW YORK.

SAFETY TRAIN-STOP MECHANISM.

1,349,489.

Specification of Letters Patent. Patented Aug. 10, 1920.

Application filed November 22, 1916. Serial No. 132,871.

To all whom it may concern:

Be it known that I, JOHN W. BINGLEY, a citizen of the United States, residing at Watertown, in the county of Jefferson and 5 State of New York, have invented certain new and useful Improvements in Safety Train-Stop Mechanisms, of which the following is a specification.

This invention relates to safety train stop mechanisms, designed to be so related to 10 railway signal systems and to familiar types of automatic air-brakes, as to bring the train to rest by a service application of the air-brakes if the engineer runs past a signal 15 which is set against him.

The application is caused by a magnetically operated vent-valve which vents air from the equalizing reservoir on the engineer's brake valve. At the same time a magnetically operated stop-valve cuts off the 20 main reservoir, so that this cannot feed the train-pipe, whatever may be the position of the engineer's brake-valve. Both the vent and the stop valves are actuated by an electric 25 magnet relay, which is brought into action by a track-trip of the inductive type. This last consists essentially of a fixed electromagnet on the track, energized or deenergized according to the position of the corresponding signal, and an inductive coil on the 30 train and carried thereby through the field of the fixed track magnet. The current induced in the inductive coil actuates the relay.

I illustrate a preferred form of the invention in the accompanying drawings, in which the various valve mechanisms are illustrated in section and the pipe and electrical connections are shown in diagram, as are the relay and the track trip.

40 The invention may be applied to any usual type of automatic air brake system in which the brakes are applied by a reduction in train-pipe pressure. The engineer's brake valve is provided with the usual casing 1 and operating handle 2, which is connected in the usual manner to the rotary valve 3. The rotary valve has the ordinary functions 45 corresponding to release, running, lap, service and emergency positions, but might have

more or fewer positions so far as the present 50 invention is concerned, for the rotary valve takes no part in, and cannot affect the action of the safety stop mechanism.

The casing 1 is provided with the usual pipe connections. The main reservoir connection is shown at 4, the feed valve connection at 5, the train-pipe connection at 6, and the equalizing reservoir connection at 7. The main air-pipe, leading from the main reservoir (not shown) is illustrated at 8: 60 and 9 is the pressure reducing feed valve, interposed between the main air pipe 8 and the feed pipe 10. The equalizing reservoir is shown at 11. The duplex pressure-gage 12 is connected by the pipes 13 and 14 to the 65 equalizing reservoir 11 and main air pipe 8, respectively.

The equalizing reservoir 11 is connected to the equalizing chamber 15, above the equalizing piston 16, which is subject on its 70 lower side to train-pipe pressure. The piston 16 operates the equalizing discharge valve 17, which controls an exhaust or discharge port 18, leading from the train-pipe to the atmosphere. The pressure in the 75 chamber 15 is controlled by the valve 3, by its coaction with a port 19 in the seat of said valve. All the parts so far described are of familiar construction, and operate in the usual manner, service applications being 80 made by reducing the pressure in the chamber 15, which causes the piston 16 to rise and open valve 17 to vent train-pipe pressure. The valve 17 again closes when the 85 train-pipe pressure has fallen slightly below the reduced pressure in the equalizing chamber.

My improved safety stop mechanism operates to apply the brakes by reducing the pressure in the equalizing chamber and for 90 this purpose I make use of a vent valve 20 mounted on a branch pipe 21. The valve 20 is held closed by the pressure in the equalizing chamber and also by a spring 22. It may be forced open by a sliding armature 95 23, which is drawn down by a surrounding electro-magnet 24 when the latter is energized.

If, however, the engineer's valve should be at release or running position, air from the main reservoir would be fed to the train pipe, either directly or through the feed valve 9, and this would overcome the venting action of the equalizing discharge valve and prevent a proper application of the brakes. To prevent this I make use of a stop valve placed in the main air pipe in 5 advance of the feed valve connection, so that when the stop-valve is closed no air can feed to the engineer's valve either directly or through the feed valve. The action of this stop valve is controlled by a magnet in 10 circuit with the magnet 24.

The casing of the stop valve is shown at 25, and the valve proper at 26. The stem 27 of the valve 26 carries a piston 28, working in the cylinder 29 which has a vent port 20 30 serving to release any pressure which may exist beneath the piston. The valve 26 is normally held up off its seat by the coiled spring 31, and may be forced up off its seat and held by the threaded rod 32, in 25 case it is desired to render this part of the device inoperative. Pressure from the main air pipe 8 may be admitted above the piston 28 by a valve 33. This is mounted in a branch pipe 34, which connects with the 30 pipe 8 in advance of the valve 26. The valve 33 is held against its seat by the main air pressure and also by a spring 35. It may be forced open by a sliding armature 36 when the latter is drawn down by an 35 electromagnet, 37.

The magnets 24 and 37 are connected in series with each other, and receive current from any suitable source 38 under the control of a relay switch. A manually operated switch 39 is interposed in the circuit, and preferably is so located as to be inaccessible except when the train is at rest, so that the engineer cannot release the brakes until the train has stopped.

45 The relay switch includes an electromagnet 40 connected in circuit with the magnets 24 and 37, and a pivoted switch arm 41 coacting with a contact 42. The arm 41 is urged in circuit closing direction by a spring 50 43 (a weight may be used if preferred) and when the magnet 40 is energized is held in circuit closing position by this magnet. When the arm 41 contacts with the contact 42 the windings of the magnet 40 are placed 55 in circuit with the windings of the magnets 24 and 37. The arm 41 is, however, normally held in circuit breaking position by an electromagnet 44 connected in a secondary circuit which includes a battery or other 60 source of current 45, and inductive windings 46 having iron cores 47. The inductive windings 46 and their cores 47 are mounted on the train so as to be carried by it past and close to an electro-magnet 48 65 fixed beside the track and adapted to be

energized so as to produce a strong magnetic field whenever an associated signal is set against the passage of the train. The form of this electro-magnet is not material and types are now familiar, one of which 70 operates on open and another on closed circuit, the latter being usually preferable because a derangement of the circuit causes stopping of the train. The drawing may represent either.

75 For open circuit operation 48 would be the soft iron core of an ordinary electro-magnet whose windings 50 would be in circuit with a battery 49, the circuit being closed by the signal when the latter is set to stop 80 position, by means of any suitable switch (not shown).

85 For closed circuit operation 48 would be a permanent magnet with soft iron pole pieces carrying the windings 50. The windings 50 would be in circuit with battery 49, the circuit being opened by the signal by any suitable switch (not shown) when the signal is set to stop position. In all clear 90 positions of the signal the circuit would be closed so that the field created by the windings 50 would neutralize the permanent field of the permanent magnet.

95 It is to be noted that both devices are essentially electro-magnets, and in each case I consider such electro-magnet to be energized when an effective field is created and de-energized when the effective field is destroyed. I use the terms in the present description and claims in this sense, such use 100 being warranted by the admitted functional equivalence of the two devices.

105 In either case, when the signal is clear the magnet 48 is de-energized or creates no field and the train may pass it without effect upon the stop mechanism. When the signal is set against the engineer the magnet 48 is energized or creates a field. The inductive effect of this field on the windings 46 when the latter are moved through 110 the field by the motion of the train produces a current which momentarily overpowers the battery 45 and thus momentarily de-energizes the magnet 44. This releases the arm 41 which moves under the influence of the spring 43 to close the circuit through the arm 41 and contact 42, battery 38, and the magnets 24, 37 and 40. The magnet 40 then holds this circuit closed by attracting the switch arm 41. This allows 115 the magnets 24 and 37 to open their respective valves and hold them open continuously. As a result, since valve 20 has a greater capacity than port 19, the equalizing reservoir is vented. The valve 26 is 120 simultaneously closed. A full service application results. The brake cannot be released until the switch 39 is opened. The opening of this switch permits magnet 44 125 to restore the switch 41 to its running posi- 130

- tion, after which the switch 39 is again closed and the device is again in running condition. The leakage around the piston 28 is purposely made sufficient to permit a relatively prompt opening of the valve 26, and pressure in chamber 15 will be restored through port 19, that being a normal function of this port in release and running positions.
- 10 While the embodiment of the invention illustrated in the drawings is preferred, changes are possible within the scope of my invention. For example while the magnets 24 and 37 are normally in open circuit and apply the brakes when such circuit is closed, it is well understood by those skilled in the art that this action may be reversed by a suitable change in the magnet valves, relay switch and connections, so that the device 20 would normally be in closed circuit and apply the brakes when the circuit is opened. Obviously throughout the electrical part of the equipment since there are only two brake conditions for the automatic mechanism, 1, 25 normal running, and 2, automatic stop, either may be made to depend upon an open and the other upon a closed circuit condition at any desired point in the electrical mechanism by a proper coördination of the 30 elements of the device. Such alternative arrangements as well as minor mechanical variations fall within the scope of the invention.
- Having thus described my invention, what 35 I claim is:—
1. The combination with an automatic railway brake system, having a main reservoir and an engineer's brake valve including an equalizing discharge chamber, of an 40 electromagnetic vent valve for releasing air from said chamber; an electro-magnetically controlled stop valve for cutting off the supply of air from the main reservoir to the engineer's brake valve; a circuit including 45 both said electromagnetic valves; and means for controlling said circuit to operate said electromagnetic valves in unison.
  2. The combination with an automatic railway brake system, having a main reservoir and an equalizing discharge chamber, of an electro-magnetic vent valve for releasing air from said chamber; an electro-magnetically controlled stop valve for cutting off the supply of air from the main 50 reservoir to the system; a relay switch connected in circuit with the vent and stop valve mechanisms to actuate the same simultaneously; an electro-magnet on the track capable of being energized or deenergized; and electric means carried by the train, connected with the relay switch and adapted to operate said switch or to leave it inert according to the magnetic condition of said electro-magnet.
  3. The combination with an automatic 55 railway brake system, having a main reservoir and an equalizing discharge chamber, of an electro-magnetic vent valve for releasing air from said chamber; an electro-magnetically controlled stop valve for cutting off the supply of air from the main reservoir to the system; a relay switch connected in circuit with the vent and stop valve mechanisms to actuate the same simultaneously; an electro-magnet on the track capable of being energized or deenergized; and electric means carried by the train, connected with the relay switch and adapted to operate said switch or to leave it inert according to the magnetic condition of said electro-magnet.
  4. The combination of an automatic railway brake system having a main reservoir and an equalizing discharge chamber; electro-magnetically operable valve means for venting air from said equalizing chamber and for cutting off the supply of air from said main reservoir to the supply; a current source, a switch, and a magnet in circuit with said electro-magnetically operable valve means, said magnet when energized by the closing of the switch, serving to hold said switch closed; means exerting a constant closing tendency on said switch; a second, constantly closed circuit including inductive windings, a current source and an electro-magnet, the last named magnet normally holding said switch open, all the parts so far named being mounted on the train; and a fixed electro-magnet on the track capable of being energized to produce a field through which said inductive windings are moved by the travel of the train, the inductive windings being so arranged that the induced current over-powers the current source and thus deenergizes the switch holding magnet in circuit with such windings.
  5. The combination of an automatic railway brake system having a main reservoir and an equalizing discharge chamber; electro-magnetically operable valve means for venting air from said equalizing chamber and for cutting off the supply of air from said main reservoir to the supply; a current source, a switch, and a magnet in circuit with said electro-magnetically operable valve means, said magnet when energized by the closing of the switch, serving to hold said switch closed; means exerting a constant closing tendency on said switch; a second, constantly closed circuit including inductive windings, a current source and an electro-magnet, the last named magnet normally holding said switch open, all the parts so far named being mounted on the train; a fixed electro-magnet on the track capable of being energized to produce a field through which said inductive windings are moved.

4
by the travel of the train, the inductive windings being so arranged that the induced current over-powers the current source and thus deenergizes the switch holding magnet in circuit with such windings; and a normally inaccessible manually operable switch interposed in circuit with said electro-mag-

netically operable valve means to permit restoration of said switch to normal position after actuation.

10

In testimony whereof I have signed my name to this specification.

JOHN W. BINGLEY.
